UNITED STATES PATENT OFFICE

SAMUEL J. SWITOW, OF LOUISVILLE, KENTUCKY

DESIGN FOR A STORE FRONT

Application filed June 25, 1932. Serial No. 44,191. Term of patent 7 years.

To all whom it may concern:

Be it known that I, SAMUEL J. SWITOW, a citizen of the United States, residing at Louisville, in the county of Jefferson and State of Kentucky, have invented a new, original, and ornamental Design for Store Front, of which the following is a specification, reference being had to the accompanying drawing, forming a part thereof.

The figure is a front perspective view of a store front, showing my new design.

I claim:

The ornamental design for a store front, as shown.

SAMUEL J. SWITOW.
